(57) **CLAIM**

The ornamental design for a dosage container with lid for
adding washing agent, as shown and described.

DESCRIPTION

FIG. 1 is a front and side perspective view of a first embodiment
of a dosage container and lid;

FIG. 2 is a right side elevational view thereof;

FIG. 3 is a left side elevational view thereof;

FIG. 4 is a rear elevational view thereof;

FIG. 5 is a front elevational view thereof;

FIG. 6 is a top plan view thereof;

FIG. 7 is a bottom plan view thereof;

FIG. 8 is a front and side perspective view of the lid, shown
separately for clarity of illustration.

FIG. 9 is a right side elevational view of FIG. 8.

FIG. 10 is a left side elevational view of FIG. 8.

FIG. 11 is a rear elevational view of FIG. 8.

FIG. 12 is a front elevational view of FIG. 8.

FIG. 13 is a top plan view of FIG. 8; and,

FIG. 14 is a bottom plan view of FIG. 8.
